C. S. BARON.

SANITARY PITCHER OR THE LIKE AND MEANS FOR CONNECTING THEIR COVERS THERETO.

APPLICATION FILED MAY 25, 1918.

1,389,733.

Patented Sept. 6, 1921.

Inventor:
Charles S. Barow
By
Joseph S. Barnes,
Attorney.

UNITED STATES PATENT OFFICE.

CHARLES S. BARON, OF TIFFIN, OHIO.

SANITARY PITCHER OR THE LIKE AND MEANS FOR CONNECTING THEIR COVERS THERETO.

1,389,733.

Specification of Letters Patent.

Patented Sept. 6, 1921.

Application filed May 25, 1918. Serial No. 236,480.

To all whom it may concern:

Be it known that I, CHARLES S. BARON, citizen of the United States of America, residing at Tiffin, in the county of Seneca, in the State of Ohio, have invented certain new and useful Improvements in Sanitary Pitchers or the like and Means for Connecting Their Covers Thereto, of which the following is a specification, reference being had to

10 the accompanying drawing.

My present invention relates to pitchers, jugs, containers for liquids of the type shown in U. S. Letters Patent, No. 1,173,546 issued to me under date of February 29, 15 1916. The preferred type of cover which I use for such container is that set forth in my application for U. S. Letters Patent Serial Number 162,344, filed April 16, 1917.

My invention as herein described and 20 claimed is, however, conceived to be of broad and independent scope, in so far as it relates to means for securing a cover or lid to a container. In that regard my invention is applicable to any kind of a container for 25 liquids and to any cover suitable therefor and hinged thereto.

An object of prime importance in respect 30 to my invention is the promotion of the sanitary cleanliness of utensils of the class indicated, through the provision of means for hinging a container to its cover, which is at once effective for combining those elements in operative assemblage, and for conveniently disassembling them at will in order 35 to cleanse them.

What constitutes my invention will be hereinafter described in detail and succinctly set forth in the appended claims.

In the accompanying drawing,

40 Figure I is a top plan view of my invention in present preferred form of embodiment, showing the upper end of a container covered by a lid, the container and lid being hinged together according to the principle 45 of my invention.

Fig. II is a fragmentary medial vertical section of the subject-matter of Fig. I setting forth further details of the form of embodiment of my invention as shown in 50 Fig. I.

Fig. III is a view similar to Fig. I showing a modification of my invention as applied to a glass lid, instead of a metal lid as shown in Figs. I and II.

55 Fig. IV is a view corresponding to Fig.

II but taken of the subject-matter of Fig. III.

Fig. V is a detail fragmental view, partly in section and partly in elevation, of the hinge members, including one end of the 60 pintle, shown in Fig. I and II.

Fig. VI is a view similar to Fig. V illustrative of modifications shown in Figs. III and IV.

Referring to the numerals on the drawing, 1 in Figs. I, II, and V, indicates the body of a container of any suitable shape and dimensions. It may be made of any suitable material, such, for example, as glass, fictile material, or metal, and is preferably provided on one side with a spout 2 and on the opposite side with a handle 3.

On the top of the body 1, I provide a lid or cover 4, which, by preference, is of the type described and claimed in my application for 75 patent aforesaid, it being essential only that the lid be hinged to the body. The hinge connection between the lid and the body is preferably medially disposed so that the lid may be tilted by pressure applied on one 80 side of the hinge axis or in other words, generally speaking, on the side thereof next to the handle 3. The rear end of the lid is preferably provided with a push button 5 or projection against which the thumb may 85 find support when its pressure is exerted to open the lid.

My invention consists in providing a pintle whose shape and resiliency render it readily attachable and detachable for the 90 assemblage and disassembling of the body and the lid.

In addition to such a pintle I employ in the more highly organized development of my invention a hinge connection between 95 the body and the lid which at the same time accommodates itself to the function of the pintle and also serves to exclude the intrusion of insects between the body and the lid of a closed container.

The pintle aforesaid, designated in Figs. I, II, and V by the numeral 7, is a resilient member which, extending across the body 1, is provided near its opposite ends with oppositely projecting terminals 8. The pintle is 100 preferably bail-like in form, being composed preferably of one piece of spring wire shaped to form a back bone 9 and two side-pieces 10. The back bone preferably 105 extends from one side-piece to the other in a 110

straight line, and is preferably parallel to an axis common to both terminals 8.

The function of the pintle 7 is to hold together in operative assemblage but detachably the body and its lid. To that end it is made to engage both the body and the lid. The former it engages by the force of its resiliency, which is directed so as to drive the terminals 8 into shallow sockets 11 provided 10 for their reception, respectively, upon opposite sides of the body 1.

It may engage the lid in more ways than one. At present, I prefer to construct the lid with hinge lugs 12 as shown in the figures last above named that fit loosely but snugly within recesses 15 provided for their reception, respectively, in opposite sides of the body and at a distance above the sockets 11 that is correspondent to the length of 20 the side-pieces 10.

If the lid 4 be made of metal the hinge lugs 12 may be readily formed by shaping and bending the metal as required to fit the respective recesses 15. They may be also 25 provided with coaxial bores 16 through which the backbone 9 of the pintle may be made to extend. This construction is preferred because it conceals the major portion of the pintle within the container and unites 30 the one to the other.

If, however, the lid be made of glass, fragile material, or the like, the provision of bores in the hinge lugs would be more or less objectionable because, for example, of 35 the liability to breakage thereby incurred. In such case, I provide, as shown in Figs. III, IV, and VI, pintle seats 19 on top of the lid 17 in addition to imperforate lugs 18, below the lid. The seats 19 accommodate 40 and operatively engage, substantially in the manner already described, a pintle 20, whose only differentiation from the pintle 7 is in respect to dimensions.

The lugs 12 coöperate with their recesses 45 15 to constitute a hinge and the office of the pintle 7 is positively to hold those hinge members together in operative relationship, subject to ready disassembly as often as desired simply upon removal of the pintle. 50 The pintle performs the additional function of limiting the opening movement of the lid, owing to a slight difference between the axis of rotation imposed by the lugs 12 within their recesses 15 and the longitudinal axis 55 of the backbone 9 of the pintle. The effect referred to is indicated in Fig. II by the two positions of the side-piece 10 as shown.

A like function to that last above de-

scribed is performed also by the pintle 20 in coöperation with its seats 19, as illustrated in Fig. IV. The wider deviation of the cheek pieces shown in the figure last named 60 amounts only, in effect, to a further exemplification of the showing made in Fig. II and may be used to assist the reader to better comprehension of the principle illustrated in both figures. 65

In operation the lid 4 or 17, as the case may be, is assembled with a body 1, to which without change either lid may be adapted. Thereupon through the application of a proper pintle 7 or 20, as required, the elements named are thereby united in operative assemblage, and adapted for manipulation in use in the usual manner. 70

The method of assemblage described facilitates the taking of the utensil apart as 75 for cleaning purposes, and contributes equal facility to the reuniting of the parts as often as occasion may require.

What I claim is:

1. The combination with a receptacle provided upon opposite sides of its open end with bearings and with sockets below the same, respectively, of a lid provided with lugs working as hinge members in said bearings, and a resilient pintle, provided with a backbone engaging said lid, with side pieces, and with terminals adapted to engage said sockets for the purpose specified. 80

2. The combination with a receptacle provided upon opposite sides of its open end with open bearings and with sockets, respectively, of a lid provided with lugs working as hinge members in said bearings, and a resilient pintle provided with a backbone engaging said lid, with side pieces, and with 90 terminals adapted to engage said sockets for the purpose specified. 95

3. The combination with a receptacle provided upon opposite sides of its open end with open bearings and with sockets, respectively, of a lid provided with lugs working as hinge members in said bearings, and a resilient pintle passing through said lugs provided with a backbone engaging said lid, with side pieces, and with terminals adapted 100 to engage said sockets for the purpose specified. 105

In testimony whereof, I have hereunto set my hand in the presence of two subscribing witnesses.

CHARLES S. BARON.

Witnesses:

HELEN SWING,
L. J. WINGART.
